CLAIM

The ornamental design for a net shopping bag, as shown and described.

DESCRIPTION

FIG. 1 is a front elevational view of the net shopping bag embodying our design;

FIG. 2 is a side elevational view of the net shopping bag as shown in FIG. 1 in open configuration;

FIG. 3 is an enlarged, fragmented view of one of the grips of the net shopping bag, the other grip being identical; and,

FIG. 4 is an enlarged, fragmented view of the side seam of the net shopping bag shown in FIG. 1.
